UNITED STATES PATENT OFFICE.

MOSES PALMER, JR., OF BOSTON, MASSACHUSETTS, AND E. WILLOUGHBY ANDERSON, OF WASHINGTON, DISTRICT OF COLUMBIA.

IMPROVED PATTERN FOR MEASURING THE BODY FOR GARMENTS.

Specification forming part of Letters Patent No. **105,486**, dated July 19, 1870.

To all whom it may concern:

Be it known that we, MOSES PALMER, Jr., of Boston, Massachusetts, and E. WILLOUGHBY ANDERSON, of Washington, District of Columbia, have invented a new and valuable Improvement in Measuring-Vests; and we do hereby declare that the following is a full, clear, and exact description of the construction and operation of the same, reference being had to the annexed drawing, making a part of this specification, and to the letters and figures of reference marked thereon.

Figure 1 of the drawing is a representation of our invention adjusted on the form. Fig. 2 is a view of the same when laid on a plane surface as a pattern. Fig. 3 is a detail.

Our invention has relation to means for fitting the upper part of the body; and consists in the construction of a contractible and adjustable vest, capable of being accurately fitted to the form, and afterward of being extended flat on a plane surface, to serve as a pattern by which the fronts and backs of dresses, coats, shirts, &c., may be cut.

A vest may be considered as a bag, with four openings in it. Taking such a vest as a nucleus, we vary its capacity by lapping those portions of it which lie between the openings along the lines of the seams. The size and form of the openings are also varied by means of adjustable slides.

From the nature of its construction the same vest is capable of being fitted to individuals of different sizes, and its parts will retain their relative position after it has been removed from the form.

The vest shown as an illustration of our invention in the drawing consists of a front and two back pieces. The back is divided in order to allow the vest to be spread on a plane surface, for use as a pattern. The front might be divided instead if it were thought desirable.

In fitting for the yoke of a shirt it is not necessary that either back or front shall be divided. They may both be entire, and the separation may take place along the line of seam of either shoulder.

The letter A designates the front, usually made entire. The front as well as the back

should be of strong closely-woven cloth or leather. If cloth is employed it should be, as nearly as possible, inelastic, and the texture should be such that the threads will not readily move upon each other. The letters B B' represent the back pieces, arranged to be secured together along the central line of the back when the vest is adjusted on the person. The ends b b' b' of the back and front pieces, between the neck and arm-holes, are lapped over each other, in order that they may be movable with reference to each other, and that the vest may thereby be expanded or contracted, to suit the size of the person about the shoulders.

In a similar manner the adjacent ends of the front and backs, under the arm-holes, are lapped.

Slots c c are formed in these lapping ends, the slots extending in directions at right angles with the lines of the seams. The lapping ends are drawn closely together, and secured by means of clamping-screws z z.

The vest is now fitted to the person in so far as its general form is concerned; but in order for it to serve as a pattern the lines of the edges of the cloth in the neck and arm-holes must be indicated in their proper position and shape. The shape and position of these lines depend on the size and contour of the person, and vary with each individual. The position of a certain number of points of these lines is therefore fixed before the vest is taken off. This is done by means of the adjustable slides d d, which project from the edge of the vest, around the neck and arm-holes, in directions at nearly right angles to the edge of the vest or curvature thereof. These slides are secured by clamp-screws, and are sometimes numbered and graduated for convenience. The projecting ends are rounded. The clamp-screws z z are peculiar in their construction. The screw is perforated centrally at n.

Care should be taken in the adjustment of these clamp-screws to keep them in the required line of seam.

a a are eyelets, vertically arranged in the central line of the front.

Sometimes we employ the slots and perfo-

rated clamp-screws for the connection of the backs, lapping their adjacent edges over each other.

After the vest is adjusted to the form, and the edges of the pattern properly defined by means of the slides and slots, the clamp-screws are set and the vest taken off, the backs being separated.

It can now be spread flat on a plane surface, and, following the points given by the rounded ends of the slides *d d*, the cutter can readily and with free hand describe the pattern on paper, or mark the proper shape with chalk on the material itself.

The lines of the seams are obtained by pricking or marking through the apertures *n* of the clamp-screws *z z*.

In measuring for shirts, where only the shape of the neck and length of shoulder are required, we sometimes employ two rectangular strips of material, cutting out the curve of the neck by hand, applying them to the person from front and rear, overlapping their free ends, and marking on the lapped ends the positions of the shoulder-seams.

What we claim as our invention, and desire to secure by Letters Patent, is—

1. The adjustable vest or pattern consisting of front and back portions, attached together by means of slots *c* and perforated clamp-screws *z*, and provided with the sliding plates *d*, to determine the curvatures of the neck-slope and arm-hole, substantially as specified.

2. A vest or pattern consisting of front and back pieces having their ends *b b' b' b* overlapped, so as to fix them in relative positions, determined by the shape and slope of the body, substantially as specified.

3. The centrally-perforated clamp-screw *z*, as specified.

In testimony that we claim the above we have hereunto subscribed our names in the presence of two witnesses.

MOSES PALMER, JR.
E. W. ANDERSON.
